UNITED STATES PATENT OFFICE.

JOHN W. RICHMAN, OF GILROY, CALIFORNIA.

POWER-DRIVEN BRUSH.

Application filed December 27, 1923. Serial No. 682,932.

My invention is an improved power driven brush, particularly adapted for cleaning walls, ceilings, woodwork, etc.

The object of my invention is to provide a brush which is simple in construction, and inexpensive to manufacture.

Another object is to provide a detachable handle or stand; so that the brush may be portable for the uses outlined above, or stationary for use as a clothes brush, etc.

In the annexed drawing in which my invention is illustrated;

Figure 1 is a side view partly in section of my brush.

Figure 2 is a fragmentary sectional view of the handle mount for the brush.

Referring more particularly to the drawing, an electric motor 1 has flanges 2 and 3 formed at either end thereof. A tubular handle 4 has a flange 5 formed on the end thereof, which is bolted against the flange 3 of the motor, thus securing the motor to the handle. A tube 6 has a flange 7 on the lower end thereof, to which the flange 2 is bolted. The shaft 8 of the motor 1 extends through the tube 6 and a coupling 9 is secured to the outer end thereof.

The cleaner 10, which is preferably conical in shape, is mounted upon a shaft 11, and this shaft extends into the coupling 9 thereby securing the brush to the shaft 8, which shaft causes the cleaner to rotate.

A locking pin 12 is pivoted to the lower end of the handle 4, and extends through a hole 13 in the handle. The stand 14 has a shank 15 extending into the handle 4, and the pin 12 extends into the shank, thus holding the brush in the stand. By removing the pin the stand 14 may be removed and the shank 16 of the hand grip 17 inserted in its place. It will be understood that the invention is not limited to the exact structure disclosed, and that various modifications may be made within the scope of the appended claim. I have therefore used the term "supporting member" to indicate the stand 14, the hand grip 17, and their mechanical equivalents.

Having described my invention, I claim:

A power driven brush comprising a handle, a flange on the outer portion of said handle, an electric motor, a casing therefor, a flange on each end of said casing, one of said flanges of the casing being adapted to abut against the flange on the handle, a tube, a flange thereon, said last mentioned flange being adapted to engage the other flange of the casing, a shaft extending thru said tube and operatively connected to said motor and a cleaner operatively connected with said shaft.

In testimony whereof I affix my signature.

JOHN W. RICHMAN.
